2 Sheets-Sheet 2

UNITED STATES PATENT OFFICE

JOHN A. LUCAS, OF MONESSEN, PENNSYLVANIA

AEROPLANE SWING

Application filed January 24, 1931. Serial No. 511,060.

This invention appertains to amusement devices and more particularly to a swing constructed in such a manner that children will obtain therefrom healthful exercise and a maximum amount of amusement and pleasure.

One of the primary objects of my invention is the provision of a swing constructed to simulate an aeroplane, with novel means for mounting the swing from an overhead support with operating means for bringing about the proper oscillation of the swing, the manipulation of the operating device forming the exercising medium for the child or children.

Another salient object of my invention is the provision of novel means for operating a propeller arranged at the front of the swing during the actuation of the operating device, whereby the propeller will be rotated, so that the entire device will more closely resemble and simulate the appearance of an actual aeroplane, and thereby afford further amusement for the children.

Another important object of my invention is the provision of means whereby the operating device for the swing can be operated by either the hands of the children or by the feet of the children, or by the hands and feet operating in proper conjunction with one another, whereby substantially all of the muscles of the user will be brought into play.

Another important object of my invention is the provision of novel means for mounting the propeller shaft and novel means for actuating the propeller shaft, with novel means for connecting the propeller to the shaft whereby the propeller will be only rotated in one direction irrespective of the direction of rotation of the propeller shaft.

A still further object of my invention is to provide an improved amusement device in the form of a swing for children, which will be durable and efficient in use, one that will be simple and easy to manufacture, and one which can be placed upon the market at a reasonable cost.

With these and other objects in view, the invention consists in the novel arrangement, construction, and formation of parts, as will

be hereinafter more specifically described, claimed, and illustrated in the accompanying drawings in which drawings;

Figure 1 is a side elevation of my improved swing.

Figure 2 is a top plan view thereof.

Figure 3 is a vertical longitudinal section through the front body portion of the swing.

Figure 4 is a detail section taken on the line 4—4 of Figure 3 looking in the direction of the arrows, illustrating the means for operatively connecting the hub of the propeller with the propeller shaft, and

Figure 5 is a transverse section through the body of the aeroplane wing taken on the line 5—5 of Figure 3 illustrating the connection between the operating handle and the propeller shaft.

Referring to the drawings in detail, where-in similar reference characters designate corresponding parts throughout the several views, the letter A generally indicates my improved swing, which comprises a body 10 shaped to simulate the appearance of the fuselage of an aeroplane. The body 10 is preferably shaped from wood and can be in the nature of a narrow plank of wood. The rear narrowed end of the body 10 carries the tail 11 of the aeroplane. The upper edge of the body adjacent to the front thereof is provided with a substantially horizontally disposed wing shaped member 12 to further add to the appearance of an aeroplane. The body 10 directly in rear of the wing 10 can have its upper edge recessed for the reception of suitable seats 13, and 14, which can be provided with backs 15 and 16 respectively. It is to be noted that children straddle the body of the aeroplane and sit upon the seats 13 and 14.

The wing 12 on each side of the body 10 is provided with slots 17, which slots extend transversely of the wing but longitudinally of the body 10. The body 10 directly below the slots 17 is provided with a horizontally disposed slit 18, and a forwardly extending bore 19 which opens out through the front end of the body 10 and into the slot 18. The bore 19 and the slot 18 receive the rotatable propeller shaft 20 and suitable bearings 21, 22,

and 23 are provided for the said shaft. The end of the shaft 20 at the rear thereof is twisted to form a spiral, as indicated by the reference character 24.

- 5 The rear bearing 23 is carried by an open frame or guide 25, which slidably receives the actuating nut 26. This actuating nut 26 is provided with a spiral bore to receive the spiral portion 24 of the propeller shaft 20.
- 10 Formed or secured to the propeller shaft 20 is a collar 27 for engagement with the bearing 22 for limiting the forward movement of the shaft.

Extending through the slots 17 are a pair 15 of companion operating handles 30, connected to the body 10 above the slot 18 by suitable bearing bolts 31, whereby the handles can be rocked back and forth. These handles are provided with longitudinally extending 20 slots 32, which receive pintles 33, threaded into the sides of the operating nut 26. It is thus obvious from the description so far that upon actuation of the operating handles 30 that the shaft 20 will be rotated back and 25 forth due to the connection of the nut 26 with the spiral portion 24 of said shaft.

The propeller shaft is utilized for rotating the propeller 34 but I only wish to rotate the propeller in one direction so that the entire 30 device will more closely simulate an aeroplane. I therefore rotatably mount the hub 35 of the propeller 34 on the propeller shaft and pivotally secure to the hub ratchet dogs 36, which are normally urged into engagement 35 with the ratchet wheel 37 suitably secured to the propeller shaft 20 by means of leaf springs 38. Thus during rotation of the propeller shaft 20 in one direction the ratchet teeth of the wheel will engage the 40 ratchet dogs 36 and rotate the hubs, so that on the reverse direction of rotation of the shaft 20 the ratchet teeth will merely slide by said dogs and thus not turn the propeller.

Pivotaly connected to the body 10 in rear 45 of the seats 13 and 14 are pairs of swing operating links 40 pivotally connected to the body by means of a pivot bolt 41. The lower ends of the operating links 40 are connected to the lower ends of the handles 30 by means of 50 connecting rods 42. These connecting rods 42 are pivotally connected to the links 40 and the handle 30 by means of suitable pivot bolts 43 and 44. The front pivot bolt 43 may support ground engaging wheels 45 which can 55 simulate the landing wheels of an aeroplane. This bolt can also be extended to provide foot rests for the users of the swing and as means for permitting the operation of the connecting rods 42 by the feet of the user.

60 The swing is suspended from the overhead support, which can be considered as the ceiling of a port, a specially constructed frame or any preferred or desired supporting structure. The wings, adjacent to the opposite 65 ends thereof are provided with a pair of

supporting chains 46, and the upper ends of the chains are secured to the support. A third supporting chain 47 is connected to the upper ends of the swing operating links 40.

I can also provide a foot rest 48 carried 70 directly by the connecting rod 42 which is disposed in front of the rear seat 14 whereby the child seated on this seat can likewise operate the swing.

When the connecting rod 42 is being operated either by the foot rest 48 or by handles 30, the links 40 will be swung back and forth, which motion will be transmitted to the supporting chain 47, bringing about the oscillating movement of the swing, the speed of 80 which can be gradually increased as the swing gains momentum. The operation of the handles 30 either under influence of the direct operation of the handle or by the foot rest will cause the turning of the propeller 85 34, as heretofore stated.

From the foregoing description, it can be seen that I have provided a novel swing, which will afford a maximum amount of pleasure for children and at the same time 90 give the children the desired exercise. It is to be also noted that I have provided an exceptionally attractive swing which is of an exceptionally simple and durable character, and which will be comparatively inexpensive 95 to manufacture.

I also prefer to provide side plates (not shown) for closing the slots 18 so as to prevent the catching of the children's clothes in the nut 26 and the spiral 24. 100

Changes in details may be made without departing from the spirit or the scope of this invention, but:—

What I claim as new is:

1. An aeroplane swing comprising a body 105 shaped to simulate the appearance of a fuselage of an aeroplane, a wing connected with the upper edge of the body, supporting chains secured to the wings, operating handles pivotally connected to the body adjacent to the forward end thereof, operating links pivotally connected to the body adjacent to the rear end thereof, a connecting rod, means pivotally connecting the connecting rod to the lower ends of the handle and to the lower ends of the links, said connecting rod constituting a foot rest, and supporting chains connected with the upper ends of the operating links. 110

2. An aeroplane swing comprising a body 120 shaped to simulate a fuselage, a wing connected with the upper edge of the body, supporting chains secured to the wing, operating handles pivotally connected to the body adjacent to the front end thereof, operating links pivotally connected to the body adjacent to the rear end thereof, a supporting chain pivotally connected to the upper end of the links, a connecting rod pivotally connected to the lower terminals of the operating han- 125 30

dles and the operating links, a propeller shaft, having a spiral portion, a nut having a spiral form receiving the spiral portion of the shaft, and pintles carried by the nut connected with the operating handles.

3. An aeroplane swing comprising a body shaped to simulate a fuselage, a wing connected with the upper edge of the body, supporting chains secured to the wing, operating handles pivotally connected to the body adjacent to the front end thereof, operating links pivotally connected to the body adjacent to the rear end thereof, a supporting chain pivotally connected to the upper end of the links, a connecting rod pivotally connected to the lower terminals of the operating handles and the operating links, a propeller shaft, having a spiral portion, a nut having a spiral form receiving the spiral portion of the shaft, pintles carried by the nut connected with the operating handles, a propeller mounted on the propeller shaft, and a ratchet and dog mechanism connecting the propeller with the propeller shaft.

25 In testimony whereof I affix my signature.
JOHN A. LUCAS.
